CATHODE-RAY BEAM DEFLECTING
CIRCUITSOtto H. Schade, West Caldwell, N. J., assignor to
Radio Corporation of America, a corporation of
Delaware

Application June 30, 1943, Serial No. 492,868

2 Claims. (Cl. 175—335)

1

This invention relates to an improvement in cathode ray beam deflecting circuits, and more particularly, in circuits used for electromagnetically deflecting a cathode ray beam in such a manner that a high degree of linearity of deflection and stability of amplitude of deflection may be maintained.

Where a cathode ray tube is used to produce luminous indications, it is frequently desirable to deflect the cathode ray beam in the tube at a predetermined constant rate of speed across the screen of the tube. This is particularly true in the case of television receivers where the linearity of deflection should be maintained at the highest possible degree in order that no distortion will be present in the produced television picture. It is also desirable that the degree of deflection or the deflection amplitude be maintained constant in order that distortion will not occur and in order that the dimensions of the produced image will not be altered.

It is well known that a cathode ray beam may be deflected by electrostatic or electromagnetic fields, and the latter form of deflection is the type with which the present invention is concerned. Various circuit arrangements have been provided for improving the linearity of beam deflection in electromagnetic deflection circuits, but in most instances true linearity is not completely obtained, with the result that the rate of deflection of the cathode ray beam across the screen is not absolutely uniform throughout the entire deflection interval.

By means of the present invention, a circuit arrangement has been provided whereby a high degree of linearity may be accomplished in a cathode ray beam deflection circuit. It is also possible by means of the present invention to maintain the amplitude of deflection substantially constant irrespective of changes in operating conditions and variations in the voltages applied to the tubes as may occur in normal operation of the system.

The purposes of the present invention are in general accomplished by utilizing degenerative feedback in the deflection system, the system having inherently relatively small wave form distortion, with the result that a very high degree of linearity of deflection will result. By the same arrangement it is also possible to maintain the amplitude of deflection substantially constant in spite of operational "drifts" that may occur during the normal operation of the system. Through the use of the present invention, it is also possible to maintain a high degree of lin-

earity of deflection over a considerable range of frequencies, and accordingly the present invention may be used in a wide variety of apparatus wherein cathode ray tubes are employed.

5 The present invention may also be applied to deflection circuits wherein the deflection tubes are operated in either class A or class B.

It is, therefore, one purpose of the present invention to provide a circuit for electromagnetically deflecting a cathode ray beam in which a high degree of linearity of deflection may be maintained.

15 Another purpose of the present invention resides in the provision of a circuit for electromagnetically deflecting a cathode ray beam in which the amplitude of deflection may be maintained substantially constant irrespective of normal operational changes in the system.

20 Still another purpose of the present invention resides in the provision of a circuit for electromagnetically deflecting a cathode ray beam in which a high degree of linearity is produced even though low percentages of harmonic distortion may occur in the various tubes used in 25 the deflection circuit.

Still another purpose of the present invention resides in the use of degenerative feedback in a circuit for electromagnetically deflecting a cathode ray beam thereby to improve the linearity of 30 deflection and to maintain the amplitude of deflection stable.

35 A still further purpose of the present invention resides in the application of degenerative feedback in a cathode ray beam deflecting circuit where the deflection tubes are caused to function in either class A or class B operation.

Still another purpose of the present invention resides in the provision of means in a circuit for electromagnetically deflecting a cathode ray beam wherein a potential drop is produced as a 40 result of the flow of the beam deflection current, the produced potential drop being utilized in a degenerative manner to improve linearity of deflection and to maintain the amplitude of deflection 45 uniform.

Various other purposes and advantages of the present invention will become more apparent to those skilled in the art from the following detailed description, particularly when considered 50 in connection with the drawings wherein:

Figure 1 represents one form of the present invention; and

Figure 2 represents a modification of the circuit of Figure 1.

55 Referring now to the drawings, and partic-

ularly to Figure 1 thereof, there is shown an electron discharge tube 10 which includes a cathode, a control electrode and an anode. The cathode of tube 10 is connected directly to ground or a point of fixed potential, whereas the control electrode is connected to one of the input terminals 12 in order that a voltage variation of the desired wave form may be applied thereto. The anode of tube 10 is connected, by way of load resistor 16, to positive terminal 14 (to which a source of positive potential is applied). The anode of tube 10 is also connected to ground by way of a resistance-capacitance circuit including resistance 18, coupling condenser 20 and a further condenser 22. The two condensers 20 and 22, as well as the resistance 18, are connected in series to form the resistance-capacitance circuit.

The control electrode of tube 10 is supplied with a series of negative impulses, as represented by the curve 24 in the drawing. These impulses occur at a frequency corresponding to the desired deflection frequency. Tube 10 is normally conducting, but is intermittently rendered substantially non-conducting by the succession of negative impulses applied to the control electrode thereof. During these non-conducting intervals, the series condensers 20 and 22 are charged through resistances 16 and 18, and are subsequently discharged by the tube 10 during its conducting intervals. As a result, a voltage variation is produced at the junction of the series condensers 20 and 22 similar to that represented by the curve 26.

The resistance-capacitance circuit forms an integrating circuit responsive to the potential variations at the anode of tube 10, these potential variations corresponding to the applied pulse series 24 except that their polarity is reversed. The capacitance 20 should preferably be chosen to have a value equal to about twice the capacitance of the condenser 22. With such an arrangement the linearity of the sawtooth shaped voltage variations 26 present at the junction of the condensers 20 and 22 can be made very good if only a relatively small percentage of the full anode voltage is used.

The voltage variation represented by the curve 26 is applied to the control electrode of tube 30, which includes at least a cathode, a control electrode and an anode, but which is preferably of the screen grid type. The cathode 32 of the tube 30 is connected to ground by way of cathode resistance 34, and the anode of tube 30 is connected to the positive terminal 14 by way of anode load resistance 36. When the potential of the control electrode of tube 30 is varied by the voltage variation appearing at the junction of condensers 20 and 22, a corresponding voltage variation of sawtooth wave form will be produced at the anode of tube 30, as indicated by the curve 39. These voltage variations are then applied to the control electrode of a power deflection tube 40 by way of coupling condenser 38. The control electrode of tube 40 is connected to ground by way of grid resistor 42. The cathode of tube 40 is connected to ground by way of cathode resistance 44, in order that the potential drop thereacross will produce the desired relative potential between the cathode and control electrode of the tube. It is preferable that some degeneration be present in the tube and, as a result, no by-pass condenser is connected in parallel with the cathode resistance 44.

The power deflection tube 40 is preferably of the beam power type, and includes a cathode, control

electrode, screen electrode and anode. The screen electrode may be connected directly to the positive terminal 14, whereas the anode of tube 40 is connected to the positive terminal by way of the primary winding 46 of transformer 48. A damping resistance 50 and condenser 52 are connected in series across the primary winding 46 of the transformer. The transformer 48 is also provided with a secondary winding 54, one terminal 10 of which is connected to ground, and the other terminal of which is connected to a contact point 56. The anode of tube 40 is connected to another contact point 58, and switch arm 60 is provided for cooperating selectively with one or the other of contact points 56 or 58.

The deflecting coil or coils 62 for electromagnetically deflecting the cathode ray beam are then connected between the movable switch arm 60 and the cathode of tube 30, with condenser 64 interposed in the cathode connection. By means of the switch arm 60, the deflecting coil 62 may then be energized directly from the anode of tube 40, or it may be energized through the transformer 48 from the voltage induced in the secondary winding 54.

When voltage variations of sawtooth wave form, such as represented by the curve 39, are applied to the control electrode of tube 40, the desired current variation in the anode circuit of tube 40 is produced such that substantially linear deflection of the cathode ray beam results.

By reason of the fact that the deflection coil current flows through the resistance 34 in the cathode circuit of tube 30, a negative feedback voltage is produced by a corresponding potential drop across resistance 34. Accordingly, the current in the plate circuit of tube 30 is affected both by the voltage variations applied to the control electrode of tube 30 and by variations in the potential drop across the cathode resistance 34. These two voltages add in phase but with opposing polarity, i. e., in a degenerative sense. When degenerative feedback is provided in this manner, the circuit shown in Figure 1 will operate to deflect the cathode ray beam at substantially any scanning frequency, and a high degree of linearity of deflection will result. Furthermore, the amplitude of deflection will be maintained substantially constant.

For most efficient operation, it is desirable that the system inherently have good linearity since departure from strict linearity, when corrected by degeneration, can only be improved by the same percentage as the gain or degree of amplification is reduced. In order, therefore, to not excessively reduce the gain of the deflection system, it is preferable that the system have inherently fairly good linearity so that a minimum amount of degenerative reaction is necessary in order that the desired high degree of linearity of deflection may be accomplished.

Before feedback can be effective to reduce or compensate for distortion, it is necessary that the tube into which the feedback voltage is injected, as well as all tubes following that tube, be in an operating condition during the time that the feedback is to be effective. Accordingly, if the degenerative feedback shown in Figure 1 is to be effective over the entire deflection stroke, then it is necessary that tubes 30 and 40 be operated in class A operation. When class AB or class B operation is employed, i. e., when the tube is inoperative during a portion of the cycle, naturally the tube is inoperative during the cut-off period and hence cannot reduce distortion during

this period. The circuit shown in Figure 1, therefore, employs tubes with class A operation, and when degenerative feedback is employed such as shown in the figure, a high degree of linearity of deflection may be maintained and the degree or amplitude of deflection may be held substantially constant.

A modification of the present invention is shown in Figure 2 in which a modified form of degenerative feedback is employed. In this circuit, a tube 70 is provided having at least a cathode, a control electrode and an anode, the tube being preferably of the beam power type. A condenser 72 is provided, one plate of which is connected to input terminal 74, the other plate being connected to ground by way of an adjustable resistance 76. The condenser 72 is the discharge condenser on which a rising sawtooth voltage is generated from a preceding tube (not shown), so that a voltage variation of substantially sawtooth wave form, as represented by curve 75, is present at the input terminal 74, and this voltage variation is applied to the control electrode of tube 70 by way of coupling condenser 78. The control electrode of tube 70 is connected to ground by grid resistor 80, and the cathode of tube 70 is also connected to ground by cathode resistance 82, this resistance being by-passed by condenser 84.

The anode of tube 70 is connected to a positive terminal 86 (to which a source of positive potential is applied) by way of series connected inductance 88 and resistance 90. The resistance 90 has a value generally several times the resistance of the deflecting coils, and may be eliminated if the resistance of the choke coil 88 is sufficiently high. The deflecting coils 92 for electromagnetically deflecting the cathode ray beam are connected between the anode of tube 70 and the junction of condenser 72 and resistance 76 by way of a condenser 94. This condenser 94 is preferably of relatively large capacity and may be of the electrolytic type.

A controlled damping tube or inverted tube 96 is also employed, and this tube includes at least a cathode, a control electrode and an anode. The cathode of tube 96 is connected directly to the anode of tube 70, while the anode of tube 96 is connected to the positive terminal 86 by way of adjustable resistance or potentiometer 98. The anode of tube 96 is also connected to a single-pole double-throw switch 100 in order that the anode may be connected selectively (1) to the junction of condenser 94 and deflecting coils 92, and thence to resistance 76 by way of low alternating current impedance or condenser 94, or (2) to ground by way of condenser 102.

The tube 96 is preferably of the beam power type, in which case it also includes a screen electrode to which an adjustable potential may be applied by means of the potentiometer 104. The resistance element of this potentiometer is connected between the positive terminal 86 and ground, and the movable contact of the potentiometer is connected to the screen electrode by resistance 106. A decoupling condenser 108 is connected between the screen electrode and ground.

The control electrode of tube 96 is connected to its cathode by means of two series connected parallel resistor-condenser combinations, the first of which includes resistance 104 and condenser 112, and the second of which includes resistance 114 and condenser 116.

With the circuit arrangement as described,

when a voltage variation of sawtooth wave form is applied to the control electrode of the tube 70, a current variation is produced in the deflecting coils to electromagnetically deflect the cathode ray beam in a substantially linear fashion. Inasmuch as a portion of the current in the deflecting coils, depending on the position of switch 100, must flow through the resistance 76, a potential drop is produced thereacross which is also effective to modulate the potential of the control electrode of tube 70. This provides degenerative feedback which is fully effective and caused by the currents of tube 70 and tube 96 when the switch arm 100 is connected to the condenser 102. The resistance 101 serves them as an isolation resistor, providing a direct current path for the beam centering current. The resistor 101 may be replaced by an appropriately chosen choke. Partial feedback results when the switch arm 100 is moved into contact with the junction of the deflecting coils 92 and the condenser 94 (as shown in the drawing) as then the current component of only the deflection power tube 70 causes a degenerative voltage on resistor 76.

The inverted controlled tube 96 or damping tube is effective to improve efficiency and linearity, and is normally conducting over at least the initial portion of each deflection stroke. The amount of current passed by tube 96 is determined in accordance with the values of the parallel resistance and condenser combinations 110, 112 and 114, 116. The use of such combinations is shown and described, for example, in Schade U. S. Patent No. 2,382,822, issued on August 14, 1945. Linearity of the deflection can in part be controlled by the potentiometer 104, since an adjustment of this potentiometer determines the amount of current permitted to pass through tube 96. The adjustable resistance 98 is effective for centering the cathode ray beam on the screen.

The degree of degeneration or inverse feedback can be regulated by an adjustment of resistance 76 since an increase in the size or value of resistance 76 naturally increases the degree of degeneration. If the degree of degeneration is increased, the amplitude of deflection is decreased, with the result that a variation in size of the scanned raster may be controlled by varying the value of the resistance 76. Conversely, if the value of resistance 76 is decreased, the degree of degeneration is decreased and the size or amplitude of deflection is correspondingly increased.

Accordingly, by reason of the particular circuit arrangements and the degenerative feedback provided therein, it is possible to maintain excellent linearity for very large deflection size or amplitude variations. This is a result which has heretofore been difficult, if not impossible, to achieve. When the potentiometer 104 is properly adjusted to produce good linearity without feedback, a very high degree of linearity and stability may then result by reason of the degenerative feedback, and the degree of degenerative feedback may then be utilized to control the size or amplitude of deflection.

Since a damping or controlled inverted tube 96 is included in the circuit shown in Figure 2, it is possible that tube 70 may be operated as class AB if desired, although the circuit arrangement shown and described is most effective for class A operation of the tube.

Although the circuits shown in Figures 1 and 2 have been described somewhat in detail, it is

obvious that various modifications of these circuits will become apparent to those skilled in the art. Even very simple deflection circuits and those of the intermittent or pulse type may be conveniently provided with the degenerative feedback shown in the two figures, and it is to be understood that any and all modifications of the circuits shown in Figures 1 and 2 should be considered within the purview of the present invention.

Having now described my invention, what I claim as new and desire to have protected by Letters Patent is:

1. A cathode ray beam deflecting circuit comprising means for generating a voltage variation of substantially saw tooth waveform, an electron discharge tube having at least a cathode, a control electrode and an anode, means including an impedance for maintaining the anode positive with respect to the cathode, a grid resistance for connecting the control electrode to a point of fixed potential, a condenser and an adjustable resistance connected in series between the control electrode and the point of fixed potential, means to apply the generated voltage variation of saw tooth waveform to the control electrode of said tube to produce corresponding potential variations at the anode thereof, a cathode ray beam deflecting coil, means to couple the cathode ray beam deflecting coil to the anode of said tube so that current variations will be produced therein in response to the potential variations present at the anode of said tube, an inverted discharge tube effectively connected in parallel with the deflecting coil, and means including a condenser to direct at least a portion of the deflecting coil current variations through the adjustable resistance associated with the control electrode of said tube whereby a potential variation will be produced across said adjustable resistance, the potential variations being in phase with the generated voltage variations of saw tooth waveform and having a polarity opposite to that of the generated voltage variations.

2. A cathode ray beam deflecting circuit comprising means for generating a voltage variation of substantially saw tooth waveform, a deflection power tube having at least a cathode, a control electrode and an anode, means including an impedance to maintain the anode positive with respect to the cathode, means including a resistance to connect the control electrode of said tube to a point of fixed potential, a condenser and an adjustable resistance connected in series between the control electrode and the

55

point of fixed potential, means to apply the generated voltage variations to the control electrode of said tube to produce corresponding voltage variations at the anode thereof, a cathode ray beam deflecting coil, means including said adjustable resistance to connect the deflecting coil between the anode of said tube and the point of fixed potential so that current variations are produced in said deflecting coil and in said 10 adjustable resistance in response to the voltage variations at the anode of said tube, an electron discharge path effectively connected in parallel with said deflecting coil, and means to alter the impedance of the electron discharge path in accordance with the waveform of the potential variation at the anode of the deflection tube, the potential variations caused by the current variations in said adjustable resistance being effective to modulate the potential of the control 15 electrode of said deflection tube, the potential variations being in phase with and degenerative with respect to the degenerated voltage variations of substantially saw tooth waveform.
